2,584,937

FLOOR FURNACE VALVE

Casper S. Stuckenholz, South Euclid, Ohio, assignor to The W. J. Schoenberger Company, Cleveland, Ohio, a corporation of Ohio

Application April 25, 1947, Serial No. 743,957

4 Claims. (Cl. 251—164)

1

This invention relates to gas control valves and specifically to a main and pilot gas control valve for an under-floor furnace (usually called floor furnaces). Such a valve is shown in C. S. Stuckenholz Patents 2,284,994 to 2,284,666, inclusive, owned by the assignee hereof.

When a single control valve is used for both main gas supply and pilot gas supply, it is required, for safe furnace operation, that turning off of the pilot gas shall only be accomplished as a special manipulation of the control. It is also considered necessary that a special operation shall be required in order to move the control valve from such pilot-cut-off position beyond the position in which the pilot gas is again turned on. The second arrangement is in order that the user will make certain that the pilot is lighted before supplying gas to the main burner.

Floor furnaces are usually controlled by a long rod leading from the main control valve through a gridded opening in the floor of the building served by the furnace and, heretofore, both pilot and main burner gas could be admitted to the furnace by permitting operation of such rod alone. In the valve according to the Stuckenholz patents, a special manipulation of the rod, such as endwise or axial movement of it, was necessary in order to adjust the valve beyond its normal main burner control range of turning movement into pilot-low and pilot shut-off positions. Since cutting off of the pilot gas necessitates re-lighting of the pilot before the gas is again supplied to the main burner, the required special manipulation of the control rod was insufficient in many cases to assure safe operation in the hands of inexperienced or careless users of floor furnaces. The principal object of the present invention is to provide, in connection with a floor furnace valve or the like, normally inaccessible means enabling turning off and/or on of the pilot gas supply.

Another object is to provide, in a single valve designed to control both main burner and pilot gas supply, in a floor furnace or similar installation, a device normally inaccessible to the user, which device requires a special operation independent of the usual operating rod or handle to enable both turning off and turning on of the pilot gas supply.

A specific object is to provide a single control valve for a floor furnace main and pilot gas supply, including a device accessible only by removing a cover plate or grill through or past which the usual control handle extends.

Another object is to provide a floor furnace gas

2

valve control, including a connection between the usual long or unwieldy valve-positioning rod and the valve plug, whereby the valve plug cannot be unseated by any possible manipulation of the rod.

Other objects and features will become apparent from the following description of a preferred form of the invention.

Figure 1 is a fragmentary assembly view, showing the valve and its control rod and safety pilot control linkage;

Figure 2 is a sectional plan view of the valve taken as indicated at 2—2 in Figure 1;

Figure 3 is a central vertical sectional view through the valve, taken as indicated at 3—3 on Figure 2;

Figure 4 is a horizontal sectional view in vertically offset planes according to the line 4—4 on Figure 1;

Figure 5 is a detail sectional plan view taken 20 as indicated by the line 5—5 on Figure 3; and

Figure 6 is an exploded view showing the valve plug and the principal adjustment devices associated directly therewith.

The valve, as illustrated, is arranged to perform essentially the same control functions as effected, for example, by Patent 2,284,995. Terms "vertical," "horizontal," etc. are used herein for convenience only. A single plug is arranged to control main burner gas flow through 30 a main passage of the plug and, additionally, to control flow of gas to a pilot burner either for "automatic" pilot operation or "manual" pilot operation, those terms being fully explained in the patent just mentioned, Fig. 26 thereof showing the automatic control arrangement.

Referring to Figs. 1 to 4 hereof, the valve assembly 1 comprises a main body 2, having inlet and outlet threaded sockets 3 and 4, respectively communicating with a central vertical conical bore 5 through reduced diameter ports 6 and 7. The body has a mounting flange 8 by which it is rigidly secured to the furnace structure as by attaching bolts or screws (not shown). The plug 10 of the valve seats downwardly in the tapered bore 5 as shown particularly by Fig. 3 and in the full on position a main diametral transverse passage 11 of the plug registers at its opposite ends with the ports 6 and 7. The plug is free to be turned therefrom to various positions, 50 gradually restricting the main burner gas supply, as is usual. The pilot ports (described below) may be so arranged that, as the main gas supply is cut off, the pilot gas supply is gradually restricted but not reduced to such extent that the pilot might fail to remain lighted.

At one side of the body 2, the same is enlarged at 12 to receive two pilot gas tube connections or plugs (none shown) entering the valve body at respective threaded sockets 14 and 15, preferably in the same horizontal plane. The socket 14 may be connected to a pilot branch feed line from a suitable main which also supplies the main burner gas to the threaded socket 3. Such a connection is for an automatic control as described in Patent 2,238,495. The threaded socket 15 receives, in any event, a branch line leading to the pilot burner. When the burner equipment is used for manual pilot control, the socket 14 is customarily sealed with a threaded plug.

In order to provide an adjustable pilot gas supply directly from the inlet socket, a short bore 16 leads axially from the threaded socket 14 into intersection with a vertical bore 17 which is open at the top of the valve body and which, in turn, intersects an oblique bore 18 whose outer end opens into the threaded socket 3 so as to be open to the main gas supply line.

A suitable needle control adjustment assembly is indicated in Figs. 1 and 2, comprising an adjustment screw 20 having a conical-pointed end (not shown) aligned with the vertical bore 17 and adapted variably to restrict or close said bore. Assuming a cap or plug occupies the threaded socket 14, the pilot gas admitted to the short bore 16 past the needle valve is communicated with the main plug receiving bore 5 through an oblique passage 21, whose outer end enters the socket 14. The passage 21 enters the main bore 5 in a plane below the main gas control passage 11 of the plug. Communication between the inner end of the passage 21 and the pilot gas outlet socket 15 is through a short passage 22, shown as axially aligned with the socket 15. In the particular design shown, the passage 22 is at right angles to the main inlet and outlet ports 6 and 7.

Communication between the inner ends of the bores 21 and 22, Fig. 4, is established by a side recess or slot 23 in the plug 10, shown as parallel to the main passage 11 of the plug but below said passage and in the common plane of the passages 21 and 22. In the illustrated position of the plug 10 (same in all views), an adjustable supply of pilot gas is admitted to the pilot from the inlet socket 3, assuming the socket 14 is capped or plugged. Alternatively, in the same position of the plug ("automatic" control operation mentioned), a constant supply of pilot gas can be admitted to the socket 14 through a suitable fitting (not shown) and connected to the outlet 15 and thence to the pilot. In that event, the needle valve 20 would be closed so that none of the pilot gas supply would come directly from the main inlet 3.

Referring particularly to Figs. 1, 3 and 5, the upper generally cylindrical portion 25 of the body is reduced and threaded as at 26 beyond the upper end of the plug 10, which latter has an upwardly open diametral slot 27 and an upwardly open axial socket 28 intersecting the slots 27. Threaded to the body at 26 is a generally tubular cap or hood 30 having an inwardly overhanging top wall or flange 31 providing a round opening 31' aligned with the plug. The flange retains, in operating position, a locking and valve-positioning stem assembly 32, see Fig. 6.

The operating stem 34 is of generally cylindrical form extending (slide fit) through a control or safety locking sleeve 51 whose functions will be described later. Said sleeve 51 extends loosely through the top opening 31'. The stem 34 has

a central enlarged portion 35, flat at one side as at 36 (explained later); and a lower reduced diameter portion 37 of the stem extends a short distance into the socket 28 of the plug to compress a coil spring 38 (Fig. 3) bearing downwardly against the bottom of the plug socket 28 so that, in reacting upwardly on the stem, the spring holds the plug seated in the tapered bore 5. A cross pin 39 fixed in the reduced end portion 37 pivotally engages the opposite respective ends of the cross slot 27 of the plug, so that the stem 34 can be turned to adjust the plug 10 with reference to the various passages above described.

To hold the stem 34 in the position described above, a locking sleeve 40 is non-rotatably supported within the sleeve or hood 30. The locking sleeve, as shown particularly by Fig. 6, has a pair of diametrically extending lugs 41 at its lower edge, which seat into complementary notches in the threaded tubular extension 25 of the body 2. In order to insure that the locking sleeve and the other movable parts located thereby will always be assembled in proper relationship to the body passages and bores, the lugs 41 and their receiving recesses are aligned off center with respect to the axis of the plug or otherwise non-symmetrically arranged about said axis. Thus, the locking sleeve has only one position in which it can be assembled onto the valve body within the hood 30. The top of the locking sleeve 40 is tightly abutted by the inwardly extending flange 31 of the cap or hood 30 when the latter is screwed tightly into its final position on the threaded part of the body extension 25. The inner bore 44 of the locking sleeve terminates downwardly in an inwardly extending flange 45 and the flange overhangs a washer 46 in slightly spaced relation thereto when the flange is resting upon the top surface 47 of the plug 10. Thus the washer limits the upward movement of the pin 39 in the slot 27, while enabling a slight tilting movement of the stem 34 in a vertical plane coincident with the axis of the cross pin. Additionally, slight pivotal movement of the operating stem in the cross slot 27 is enabled by the loose fit of the sleeve 51 in the cap opening 31; so that a control rod (shown at 50), if connected rigidly with the stem 34, as it preferably is, can have a limited amount of lateral movement in all directions at its top end.

The fixed locking sleeve 40 slidably and rotatably receives the safety control or locking sleeve 51 which, in turn, is slidably but non-rotatably mounted on the large diameter portion 35 of the operating stem 34. As shown particularly at the top of Fig. 6, the locking sleeve 51 has a central bore 52 which slidably fits the circular surface portions of the enlarged diameter portion 35 of the stem 34; and a D-shaped flange 53 near the lower end of the stem 34 is complementary to the flat side 36 of the said enlarged portion 35 of the stem. The D-shaped flange 53, of the locking sleeve 51, in the position thereof illustrated in Fig. 3, is retained against gravitation downwardly by a spring pressed spherical detent element 54 (ball and spring 55, Fig. 5) projecting a short distance from the flat face 36, just beneath the flange 53, in the raised position of the safety control or locking sleeve. The locking sleeve 51 has a relatively narrow radial lug 57 projecting outwardly adjacent or opposite the internal D-shaped flange 53, and this cooperates with circumferentially spaced shoulders 57 and 58 on the locking sleeve 40 to limit the normal turning of the plug 10. The shoulders define

end walls of an upwardly open arcuate slot 59 on the locking sleeve 40.

The lug 56 of the sleeve 51 and the said shoulders 57 and 58 of the sleeve 40 cooperate to determine the amount of possible rotary adjustment of the operating stem 34 when the locking sleeve 51 is held in its normal raised position (Fig. 3), by the ball detent 54. When the lug 56 is against the shoulder 57 (position according to Figs. 3 and 4), the main cross passage 11 of the plug 10 registers fully with the inlet and outlet ports 6 and 7 for full gas supply to the main burner. When the lug 56 is against the shoulder 58, the cross passage is out of register with both said ports, cutting off main burner supply but not the pilot. Intermediate positions variably restrict the main burner gas supply as usual.

Suitable audible signal means (not illustrated) may be provided in the valve control assembly 32, as taught by my said patents, to indicate various valve stations, including full on, simmer, off and any other desired positions.

As shown by Figs. 1, 2 and 3, the control rod 50, only a small portion of which is illustrated, may be secured rigidly to the upper reduced end 60 of the stem 34 as by a set screw 61. A similar screw 62, or a cross pin, may be used to attach the control handle 63 positioned above the usual grill diagrammatically indicated at 64. The handle and control rod 50 may be pulled upwardly a limited amount but, because of the pin and slot connection of the operating stem 34 with the plug 10, lifting of the control rod cannot unseat the plug.

The grill 64 (or a small panel portion or escutcheon plate 65 thereof, shown diagrammatically as detachably secured to the main grill as by screws 66) forms a somewhat loose fitting supporting bearing (not shown) for the upper end of the rod 50. The grill or the panel 65 may, in lieu of such audible signal means as mentioned, be provided with position indications (not shown) in association with the handle 63 to inform the user of various valve plug positions.

When the lug 56 of the safety locking sleeve 51 has been turned against the shoulder 58 to establish the off position for the main gas supply, the pilot passages are still open to supply gas through the threaded socket 15 to the pilot burner, irrespective of the manner in which pilot gas is admitted to the oblique passage 21, Fig. 4. Turning off of the pilot requires only that the solid plug portion or valve land region indicated at 68, Fig. 4, be moved into closing relation to the pilot feed passage 22.

To enable low pilot flame adjustment and pilot gas cut-off positioning of the plug 10, the slot 59 of the locking sleeve 40 has a downward extension 70, one side of which is a continuation of the shoulder 58, which extension terminates at its lower end in a circumferential branch slot 71. When the locking sleeve 51, in the off position of the plug 10 in respect to main gas supply, is depressed by causing the lug 56 of the safety locking sleeve 51 to travel along the vertical slot 70 to the level of the branch slot 71, the operating stem 34 with the locking sleeve 51 may then be turned to adjust and finally cut off the pilot gas supply as mentioned above.

Operation of the locking sleeve 51 is preferably under the control of a link 72 secured as by a hooked end 73, preferably occupying the D-shaped space between the flat side 36 of the operating stem and the inner bore 52 of the locking sleeve 51 and entering an opening 73'

in said sleeve. The link 72 extends upwardly along and parallel to the control rod 50 to within a short distance from the lower side of the grill 64 or the insert panel or escutcheon plate 65 thereof. The upper end of the link 72, as illustrated, may be pivotally connected as at 74 with an operating arm 75, having parallel arm portions 76 embracing the rod and pivotally secured thereto as by any suitable pin 77. The arm 75 is rendered accessible to the furnace user, or service man, only by lifting of the grill or by removal of the escutcheon plate 65, if the grill has such a plate. Thus control of the locking sleeve 51, in order to enable movement 10 of the plug 10 to cut off the pilot gas to the pilot feed passage 22, or to adjust the pilot flame to an unusually low position, requires a sufficiently difficult operation so that turning off or such adjustment of the pilot will not ordinarily be accomplished. Usually turning off of the pilot flame is desirable only at the end of the cold weather season in order to save the expense of burning the pilot throughout protracted warm weather periods. After the pilot has 20 been turned off, the escutcheon plate or grill is of course replaced and then it is impossible, by operation of the handle 63 alone, again to turn on more than pilot gas supply without lifting the grill or the escutcheon plate. Turning on of pilot gas supply, even without relighting, is not particularly dangerous and if done by one unfamiliar with the characteristics of the installation, he or she will usually turn the pilot off again when it is observed that the main 30 burner does not start. Thus some person familiar with the installation will be called upon to re-establish use of the furnace after a protracted idle period. An experienced user or service man, after removing the escutcheon plate or lifting 40 the grill and effecting proper manipulation of the control link 72, will, as a matter of course, make certain of the existence of pilot flame before turning on the gas supply to the main burner.

45. I claim:

1. In a gas control valve, a valve body, a plug turnable in the body, operating means therefore, main and auxiliary gas control passages in the body and cooperating separate main and 50 auxiliary passages in the plug, a turn-limiting means including circumferentially spaced abutments on the body and cooperating abutment means connected with the plug and movable between said abutments to control the main gas 55 passages, additional circumferentially spaced abutments on the body cooperating with said turn-limiting means to control said auxiliary passages, and releasable rigid means normally blocking turning movement of the plug for preventing operation of the plug between the additional abutments by said operating means.

2. In a main and pilot burner gas control 65 valve mechanism, a valve body having main and pilot burner supplying passages intersecting a valve seat and a rotary plug having main and pilot burner gas control passages intersecting said seat, a guide on the body having abutment surfaces in different planes transverse to the axis of the plug, an operating stem for the 70 plug, and a sleeve drivably rigid with the stem and slidably therealong to different positions and having abutment means cooperable with the abutment surfaces of the body respectively to 75 limit the turning movement of the plug to dif-

ferent control positions in accordance with the shifted position of the sleeve.

3. The valve construction according to claim 2, wherein the guide on the body is a sleeve slotted to provide said abutment surfaces of the body and assemblable on the body in only one turned position about the axis of the rotary plug.

4. The valve construction according to claim 2 including a spring detent normally preventing sliding of the sleeve from one of its positions 10 to the other.

CASPER S. STUCKENHOLT.
